UNITED STATES PATENT OFFICE.

GEORGE COOPER, OF BENNINGTON, VERMONT, ASSIGNOR OF ONE-HALF TO
CHARLES COOPER, OF SAME PLACE.

MACHINE FOR SEWING LOOPED FABRICS.

SPECIFICATION forming part of Letters Patent No. 433,766, dated August 5, 1890.

Application filed April 2, 1890. Serial No. 346,282. (No model.)

To all whom it may concern:

Be it known that I, GEORGE COOPER, a citizen of the United States, residing at Bennington, in the county of Bennington and State of Vermont, have invented certain new and useful Improvements in Looping-Machine Attachments for Operating Trimmers; and I do hereby declare the following to be a full, clear, and exact description of the invention, such as will enable others skilled in the art to which it appertains to make and use the same, reference being had to the accompanying drawings, which form part of this specification.

My invention relates to trimming attachments for seaming or looping machines, and has for its object to provide means for connecting and operating the trimmer and to remove the strain from the needle-arm; and it consists in the construction hereinafter described, and more particularly pointed out in the claims.

Heretofore the trimming attachment has been operated by a lever-arm rigidly secured upon a hub or sleeve of the needle-arm, so that the entire strain of operating said attachment was thrown upon the connection between the needle-arm and the driving-cam. In the present instance the lever-arm is loosely mounted upon said hub or sleeve, or, if preferred, upon the journal which carries the needle-arm, so that it is capable of independent movement, and it is operated from an independent connection with the cam-disk.

Referring to the drawings, in which like letters of reference represent corresponding parts in each figure of the drawings, Figure 1 is a plan view of so much of a looping-machine as is necessary to show the relation of the trimming attachment to the driving-shaft and operating-connections. Fig. 2 is an elevation of the needle-arm, the lever-arm for operating the trimming attachment, and the actuating-cam, showing the connections between the parts. Fig. 3 is a plan view of the mechanism shown in Fig. 2, and Fig. 4 is a perspective view of the lever-arm and the coupling by which it is connected with the actuating-cam and a section of the cutter-operating arm.

50 A designates the circular holding-plate of the machine, around which the point-carry-

ing ring *a* revolves, and B the driving-shaft mounted on the bracket *b*, from which the machine is driven, power being applied to the shaft through a band-pulley C or other equivalent means. 55

D represents a trimming attachment for severing the fabric which formed the subject-matter of a separate application for Letters Patent of the United States filed by me on the 16th day of November, 1889, upon which Letters Patent No. 426,244 were granted April 22, 1890, and need not therefore be described here further than to show its construction with the operating mechanism. A circular disk E is mounted eccentrically on the end of the driving-shaft B, and has in its face a groove F, which, by reason of the eccentricity of the disk on the shaft, forms a cam-groove. 60

G designates the needle-bar, which has at one end an elongated hub or sleeve *j*, that works upon a rigid spindle J, upon which the said bar swings or vibrates. Toward its outer or swinging end the needle-bar G has a lateral projection *g*, which rests against the side of a block *i*, that fits into the groove F of the disk E, and is held thereon by a pin *h*. The groove F being eccentric to the shaft B, when the disk E revolves the block *i* moves in the groove, and the needle-bar G is vibrated back and forth as the needle performs its work. 65

A lever-arm K is loosely mounted on the same spindle J with the needle-bar or on the sleeve or hub *j* of the latter, as desired. This arm K has outwardly-projecting parallel lugs *k* at its swinging end, between which the end of a lever-arm M is held, which projects from the trimming attachment D, and through which said attachment is operated. 75

A crank pin or stud H projects from the face of the disk E at its center, which holds one end of a coupling-arm I, while the other end of the arm is pivotally connected at L with the swinging end of the lever-arm K, that is held on the spindle J. The pin H being eccentric to the shaft B, when the shaft and disk rotate the arm K will be vibrated, and this vibrating movement will operate the cutting attachment D. 90

As before stated, the arm K has heretofore been rigidly mounted on the hub of the bar G and has been operated through the con- 95

nection between the latter and the disk E, thus putting a heavy strain upon the pin *h*. By mounting the arm K loosely, so as to permit independent movement, and coupling it 5 with a separate pin on the disk E, the strain incident to the working of the cutters is taken off the pin *h* and the mechanism made more durable and much less liable to get out of repair on account of great wear and consequent 10 breakage of the pin.

Having thus fully described my invention, what I claim as new, and desire to secure by Letters Patent of the United States, is—

1. The combination, with a trimming attachment secured to the holding-plate of a looping-machine and a cam-disk upon the driving-shaft, of a vibrating lever-arm in engagement with an arm of the trimming attachment, and a coupling between said lever-arm 15 and a crank-pin on the cam-disk, substantially as shown and described.

2. The combination, with the needle-bar and cam-disk for operating the same and with the trimming attachment upon the holding-plate, of a lever-arm mounted on the spindle 20 25

with the needle-bar and having independent movement, the connection between said lever-arm and cam-disk being independent of the connection between said disk and the needle-bar and of the connection between said lever-arm and the trimming attachment, substantially as shown and described. 30

3. The combination, with a trimming attachment mounted on a holding-plate of the machine, a driving-shaft, and a disk eccentrically mounted on the shaft and having in its face a cam-groove and a crank-pin, of a needle-bar provided with a pin which projects into the cam-groove, and a lever-arm mounted on a spindle and having right-angled 35 40 projections connected with the trimming attachment, said lever-arm being connected with the crank-pin of the cam-disk by a coupling, substantially as shown and described.

In testimony whereof I affix my signature in 45 presence of two witnesses.

GEO. COOPER.
